WILLIAM E. SHORE, OF NEW YORK, N. Y.

OIL AND AIR MIXING DEVICE IN THE FORM OF VACUUM PUMPS

Application filed July 31, 1922. Serial No. 578,649.

The principal objects of the invention are, to provide a highly effective means for accomplishing the mixing of air with oil and oil vapors and to form a vacuum pump for this purpose which is adapted to operate at very high speed so as to produce practically a constant suction and discharge, and to devise a structure of extremely simple form.

The principal feature of the invention consists in the novel manner of supporting a plurality of vanes in constant radial relation to the cylinder so that there will be no radial thrust by the vanes against the cylinder wall and in the novel construction of the rotor whereby leakage of pressure through the bearing supports of the vanes is avoided.

A further important feature consists in the arrangement of a circulating chamber in the cylinder wall whereby the heat of the wall is utilized to preheat the fluid drawn to the pump before entering the intake.

In the drawings, Figure 1 is a vertical mid-sectional view through the pump.

Figure 2 is a transverse sectional view taken on the line 2—2 of Figure 1.

Figure 3 is a perspective detail of the vanes shown removed from the rotor and showing one of the end plates and the rings for supporting the vanes.

Figure 4 is a perspective detail shown partly in section of one of the members for packing the vanes in the rotor.

Figure 5 is a perspective detail of a slight modification of the vane structure showing the end plates for supporting same.

Figure 6 is a perspective detail of a portion of the rotor used with a type of vane as shown in Figure 5.

Referring to the accompanying drawings, the pump casing 1 is formed with a hollow base 2 and a cylinder 3' forming the cylindrical pump chamber 3 which communicates with the hollow base through an opening 4 and with the intake chamber 5 through an opening 6.

An outer wall 7 of the cylindrical chamber 3 is spaced from the wall 3' to form a passage 7' therebetween, thereby providing an

insulating space around the cylinder and also to form a heating conduit.

A bridge member 8 separates the base chamber from the intake chamber.

End plates 9 are secured to either side of the casing 1 and are provided with journals 10 set eccentrically to the axis of the cylinder 3'.

A shaft 11 is mounted in the journals 10 and upon this shaft is carried a cylindrical rotor 12 which is recessed into the bridge member 8 and forms a close rotating fit therewith. The ends of the rotor fit snugly against the end plates 9.

The end plates are provided with circular channels 13 concentric to the axis of the cylinder 3'. These channels are completely covered by the ends of the rotor. Within each of the channels are arranged the rotatable rings 14 and 15 which engage respectively the inner and outer diameters and between these rings are supported the sector ends 16 of the vanes 17.

The sectors 16 are rigidly connected with the vanes at each end and said sectors are spaced from each other so that the vanes will have freedom of movement in circumferential relation with the cylinder but they will always remain radial to the cylinder because of their suspension between the rings 14 and 15.

The rotor is formed with longitudinal cylindrical orifices 18. In these orifices which are spaced equidistant in the rotor and cut through the periphery thereof, are arranged the cylindrical blocks 19 which are slotted longitudinally to receive the vanes. The sections of the blocks 19 are held together by a connecting portion 20 at the inward sides and the inner edges of the vanes are formed with notches 21 to straddle the connecting members.

The cylindrical blocks 19 are free to oscillate on their own axes and consequently they adjust themselves to the changing angular relation due to the eccentric arrangement of the rotor.

It will be noted that there is no intercommunication between the several orifices 18 and

consequently there will be no leakage past the vanes.

The construction of the vanes and supporting rings and the method of sealing the vanes in the rotor may be altered and a modified construction is illustrated in Figures 5 and 6.

In the construction shown the supporting rings 22 arranged concentrically in the heads 10 of the pump are provided with parallelly arranged circumferential slots 23 in which the double segment blocks 24 are slidably fitted. The double segments are connected together by the end blocks which are preferably of 15 angle shape.

A plate 26 having a flange 27 on the outer longitudinal edge is fitted between the angle end bars 25, said flange being machined to the curvature of the interior wall of the cylinder. 20

A rotor 28 is formed with longitudinally arranged channels 29 of substantially horseshoe shape and one edge 30 is rounded.

The channels 29 are filled with oil and 25 form a seal to prevent the escape of pressure around the vane and said vane is free to oscillate within the horseshoe shaped channel while maintaining contact with the rounded edge 30 to accommodate itself to the differing axial relations between the cylinder and 30 the rotor.

A hollow base is provided with an extension 31 leading to an outlet 32. This chamber in the base forms an oil well into which 35 all larger particles of oil not completely nebulized will fall.

A by-pass 33 is arranged between the discharge chamber 5 and the hollow base so that the pump may be operated freely for starting or under low pressure conditions. 40

This passage is controlled by a suitable valve 33' so that the quantity of nebulized fuel directed into the intake side may be regulated.

The oil feed pipe 34 is preferably connected to a cross 35 and continues through 45 to the chamber in the hollow outer wall 7, a valve 36 being interposed therein.

A pipe 37 leads from the bottom of the hollow base 2 to the bottom connection of the cross, the valve 38 being interposed. The fourth connection of the cross leads upwardly having a Y 39 therein and a valve 40 being placed between the cross and the Y.

One branch of the Y extends upwardly to 55 a light fuel tank and is provided with a control valve 41. The other branch of the Y leads to a Y fitting 42 connected to the intake chamber 5. The other branch of the Y leads to an air inlet control member 43.

A pipe connection 44 connects the upper end of the hollow cylinder wall chamber with the Y 42 and a valve 45 is arranged therein.

In the operation of this pump as a nebuliz-

er for fuel oil, the oil is fed through the pipe 34 and when the valves 36 and 41 are closed and the valve 40 is open the oil feeds direct to the intake chamber. A certain amount of air is drawn in through the member 43 according to its regulation and as the rotor rotates on its axis the vanes protrude from the periphery running concentric with the cylinder and the atmosphere within the intake and the communicating cylinder area 70 is rarified. This rarification of the atmosphere at a very high rate of speed causes adiabatic expansion which results in gasification of the oil flowing into the inlet together with the air. 75

Rarification of the air and oil vapors continues around approximately 180° of the cylinder and as the vanes clear the cylinder wall 3' at the opening 4 the discharge pressure within the discharge chamber 2 flows into the rarified space between the successive vanes. A compression effect is thus produced upon the gasified oil and air mixture which has the effect of raising its temperature considerably. The continued movement of the rotor then expels the compressed oil and air mixture and in so doing creates a further compression 80 against the back pressure of the outlet. 85

The rotor is operated at a high speed of rotation resulting in practically a continuous suction and discharge which however is composed of a very rapid succession of conditions such as described. The result of such action is that adiabatic conditions prevail resulting in a most effective and thorough 90 breaking up of the oil particles and consequent intimate association with the air. 95

The heat created by the compression conditions described is partially transmitted to the rotor and to the hollow wall of the cylinder but is almost entirely absorbed by the rarification of the atmosphere and oil in the suction side of the pump consequently no internal heat is lost. Further, an insulating chamber between the inner and outer wall 100 of the cylinder prevents the outward radiation of the adiabatic heat and when the fuel oil supply is directed through the hollow cylinder wall any heat radiating from the inner wall is absorbed by the circulating oil. 110

The adiabatic expansion of the oil and air results in the production of a very finely nebulized fuel which will not readily precipitate and it may therefore be carried a reasonable distance through a conduit to a point where 115 it is desired to be used whether in a furnace or in an internal combustion engine. 120

The action of a machine such as described is effective in the handling of extremely heavy oils and crude oil at twelve Beaumé has been successfully nebulized and burnt in a furnace without applying any external heat. 125

The arrangement of the valve 41 above the Y 39 is to enable the introduction of a light oil, such as kerosene when the pump is to be 130

shut down so that the heavy viscous oil may be cleaned out of the pump before it is left to cool, otherwise it will be extremely difficult to start the pump into operation.

5. What I claim as my invention is:—

1. An oil and air mixing device, comprising a casing formed with a cylindrical inner chamber having inlet and discharge chambers connected therewith, a rotor interposed between said inlet and discharge chambers, a bye-pass connecting said latter chambers, means unaffected by the pressure of discharge for controlling the pressure flow through said bye-pass, and means for feeding liquid fuel to the intake chamber along with a quantity of supporting air to effect their intimate association under conditions of vacuum and pressure in rapid progression and final discharge into said discharge chamber.

2. An oil and air mixing device, comprising a casing formed with a cylindrical inner chamber having inlet and discharge chambers connected therewith, said casing having a passage formed therein extending around the wall of the cylindrical chamber between said inlet and discharge chambers, a liquid fuel feed pipe connected with one end of said passage in the cylinder wall and branched to connect direct to the intake chamber and to the opposite end of said passage, valves for controlling the flow of the liquid fuel to said intake chamber and passage from said feed pipe, and means for feeding a combustion supporting gas into the vacuum chamber along with the liquid fuel.

3. An oil and air mixing device, comprising a casing formed with a cylindrical inner chamber having intake and discharge chambers, a fuel circulating passage in the cylinder wall connected with said intake chamber, means for feeding liquid fuel to said circulating passage remote from its connection with the intake, means for introducing a combustion supporting gas with said liquid fuel at its point of entrance into said intake chamber, a rotor eccentrically journalled in said cylinder, and vanes carried by said rotor radial to the cylindrical chamber adapted as the rotor rotates to produce vacuum and pressure conditions on the intake and discharge sides respectively of the cylindrical chamber to draw the mixture of fuel and gas into the intake chamber and effect their intimate association under alternate vacuum and pressure conditions as said mixture is advanced through the cylindrical chamber from the intake to its final discharge into the discharge chamber.

4. An oil and air mixing device, comprising a casing formed with a cylindrical inner chamber having intake and discharge chambers leading therefrom, a rotor interposed between said latter chambers, means for feeding liquid fuel and combustion supporting gas to said intake chamber to effect their in-

timate association under progressive vacuum and pressure conditions and final discharge into said discharge chamber, a passage connecting the intake and discharge chambers beyond the cylindrical chamber, and means for regulating the flow of said discharged mixture through said passage.
